UNITED STATES PATENT OFFICE.

HAROLD E. HOUSEMAN, OF PHILADELPHIA, PENNSYLVANIA, ASSIGNOR TO STANDARD MACHINE COMPANY, OF PHILADELPHIA, PENNSYLVANIA, A CORPORATION OF PENNSYLVANIA.

STOP-MOTION FOR CIRCULAR-KNITTING MACHINES.

1,191,513.

Specification of Letters Patent. Patented July 18, 1916.

Application filed January 17, 1916. Serial No. 72,437.

To all whom it may concern:

Be it known that I, HAROLD E. HOUSEMAN, a citizen of the United States, residing at Philadelphia, county of Philadelphia and State of Pennsylvania, have invented a new and useful Improvement in Stop-Motions for Circular-Knitting Machines, of which the following is a full, clear, and exact description, reference being had to the accompanying drawings, which form a part of this specification.

In that class of circular knitting machines in which the needle cylinder turns and the cam ring is stationary, there are periods of rotation, in which the needle cylinder revolves continuously, and there are periods of oscillation, in which the needle cylinder is caused to turn back and forth through an arc of about (say) seven eightths of a full revolution. During oscillation half the needles, herein termed the rear bank of needles, are raised and held out of action, and the knitting is done on the remaining needles, known as the front bank of needles.

The changes from rotation to oscillation, and vice versa, as well as the raising and lowering of needles out of and into action, are governed from a cam disk, cam drum, or its equivalent, which in turn is actuated step by step, at the proper times, by lugs arranged at predetermined but unequal distances apart on a pattern chain, as is well known in the art.

As will be hereinafter described, certain situations may arise, especially where the pattern chain is moved by hand and thereby brought out of time with the mechanism that it governs, in which some parts of the mechanism mechanically interfere with others, resulting in damage to the mechanism; and the object of the present invention is to provide a device which in such cases will automatically stop the machine, thereby preventing damage, and also calling the attention of the operator to the fact that something is wrong with the setting or timing of the machine.

I will now describe a preferred form of mechanism for carrying out my invention, in connection with one of the various types of circular knitting machine to which my invention is applicable, and at the same time

I will point out and explain certain typical cases of interference of parts mentioned above.

The mechanism is illustrated in the accompanying drawings, in which—

Figure 1 is a sectional plan view of a portion of a circular knitting machine embodying my invention. Fig. 2 is a front view of same. Figs. 3 and 4 are more or less diagrammatic plan views showing my invention in relation to the needle cylinder under different conditions. Fig. 5 is a side view of same. Figs. 6 and 7 are enlarged fragmentary views illustrating instances of interference of parts. Figs. 8 to 12 inclusive are diagrammatic views illustrating the needle cylinder and needles under various conditions. Figs. 13 and 14 are plan views, similar to Figs. 3 and 4, of another form of mechanism. Fig. 15 is a front elevation and Fig. 16 a partial side elevation of same.

Upon the frame *a* of the machine is mounted the bed plate *b*, which carries the 75 rotatable needle cylinder *c*, the fixed cam ring *d*, and appurtenant mechanism.

The needle cylinder receives its motion of rotation or oscillation from the constantly revolving fixed pulley *e*, and is brought to a 80 stop in the stoppage of the machine by shifting the driving belt to the loose pulley *f*. The connections and driving means between the needle cylinder and the driving pulley may be of any of those known in the 85 art. For example, appropriate connections are fully described in an application filed by Harry A. Houseman, September 22, 1915, Serial No. 51,939, and need not be shown or described herein, as they form no part of 90 my invention.

Turnably mounted directly below the needle cylinder is the cam disk *g*, which, as shown in the before mentioned application, governs the operation of the needles, needle cylinder and yarn carriers, and is itself actuated by pawl *h* on slide *i* under the action of a lug on the pattern chain *j*.

Connected with cam disk *g* is a cam *o* (Figs. 1 to 12 inclusive), which, in a certain 100 position, raises by its beveled end certain mechanism which thereby causes the shift from rotation to reciprocation. A following turn of the cam disk carries cam *o* beyond

said mechanism, which is then again lowered to cause the shift back to rotation. The position of cam *o* at this time is as shown in Figs. 1 and 2, and moving in the direction of the arrow. At this time a pin *p* is in position to be raised by the forward beveled end of cam *o* just prior to the time the shift mechanism is dropping off the rear end of said cam. Pin *p* is carried on an arm *q*, 10 pivoted to a fixed bracket on the machine frame. The outer end of arm *q* is forked and made to engage between two collars on a vertical rod *r*, in such manner as to raise the rod just prior to the time of the above 15 mentioned shift. Rod *r* is slidable and turnable in brackets *s*, and carries at its upper end a short arm with a vertical pin *t*. Pin *t* is directly beneath a beveled cam *u*, carried by a bell crank *v*, pivotally mounted in proximity to the needle cylinder. The other end of the bell crank carries a beveled stop piece *w*, which in the turn of the bell crank is moved against the needle cylinder in line with the upper level of those needle butts 20 which are out of action.

The lower end of rod *r* carries an arm *x*, which normally lies in position to act upon a pin *7* to trip off a stop motion and stop the machine. Said stop motion is of known 30 design and may be briefly described as follows:—A spring pressed belt shifter *8* is slidably mounted in a bracket *9* attached to the frame of the machine in such manner that when said shifter is released it will 35 shift the driving belt from driving pulley *e* to loose pulley *f* and the machine be stopped.

In starting the machine the hand-lever 10 is moved to the left, Fig. 2, shifting the 40 belt to the driving pulley by drawing against the head *11* attached to shifter *8*. The shifter is then held in this position by means of a spring pressed catch arm *12*, which acts as a latch to hold the shifter in the position 45 of driving. Pin *7* is carried by this catch arm, so that by moving the pin, the catch will be sprung, and the machine stopped.

In order to fully understand the application of my invention, it is necessary to go 50 somewhat into the action of the needles in the course of knitting a stocking.

During the knitting of the leg portion of the stocking the cylinder is rotated and all the needles are in action under the influence 55 of the regular knitting cams. When passing from the leg portion to the heel of the stocking, and similarly when passing from the foot portion to the toe, the motion of the needle cylinder is changed from rotation 60 to oscillation, and the needles of the rear bank *k* are thrown out of action by means of their long butts. The cylinder then oscillates and knits the first half of the heel on the front bank of needles *l*, one 65 of said needles being moved out of action at

each oscillation to form the V-shape required. The needles are thus moved out of action, one at a time, first at one end of the bank and then at the other end, alternately, until only a limited number of needles in 70 the central part of the bank remain in action. At this moment a lug on the pattern chain moves the cam disk another step, which brings certain pickers into operation to reverse the foregoing action and bring 75 the needles of the front bank into action again one at a time, to form the second half of the heel. This continues and the constantly widening set of active needles increases until nearly all of the front bank are 80 again in action, before the next change takes place. This change comprises the shift back to rotation, the operation of the yarn carriers, and the lowering of all the needles of the rear bank into action again, and is timed 85 to take place just before the completion of returning the inactive needles of the front bank into action. That is, at the time of this change there will remain a couple of needles at each end of the front bank that 90 have not been brought back into action. This number may be as great as 5 or 6; the exact number is not important, provided there are not more than so many still inactive when the change to rotation occurs. 95 The next lug of the pattern chain governs this change to rotation, and if this should inadvertently occur prematurely, it would cause the following interference: At this time a new yarn is thrown into action, and 100 one of the yarn carriers *m*, Fig. 6, is brought down from the dotted to the full line position for this purpose. It will be observed that the clearance line of the throw passes through the line of needles in their upper 105 inactive position, but clears the needles that are in the lower line, *i. e.* active. The lowering of the yarn carrier occurs shortly after the end of an oscillation of the needle cylinder on its return motion, when the line of needles in the upper position is far enough around on the return motion to pass the yarn carriers. At this instant the carriers will 110 clear all the long butt needles and a few of the short butts next to them. However, if, as above stated, more than 5 or 6 such needles remain in the upper line at this time, the yarn carriers will strike them in their descent and damage will occur. The pattern chain is set by the hand wheel *n*, which 115 may be turned freely, and lugs brought prematurely into action if care is not exercised. When about half way through the heel, when certain pickers should be made operative to bring the needles, one by one, down 120 into action again, if for any reason this operation is delayed, the needles would continue to be taken up out of action until all the needles of the front bank were up in line with the needles of the rear bank. Then, if 125

the pickers are made operative, there would be no gap for them to enter the line of butts and they could not bring any needles down. The next lug on the pattern chain would 5 follow, dictating the change to rotation, and bringing into action a cam 14, which, in lowering, acts upon the butts of all the needles of both banks to bring them down into action. As seen in Fig. 7, there would be, in 10 this case, no gap in the line for cam 14 to enter, and it would therefore press the needle butts down in V-shape as shown. This occurs just as the change to rotation takes place, and the next turn of the cylinder 15 would bring certain mid-way butts 15 into contact with the end of one of the stationary knitting cams shown at 16, and damage would occur. Again, in the event of the pickers above mentioned being made operative at the right time, the following step 20 of cam disk may be made prematurely, *i. e.* before any or more than a few of the short butt needles have been returned to active position, as before stated. This condition is 25 illustrated in Fig. 4: cam 14 in lowering will strike some of the butts and bring them down into the position of those marked 15 in Fig. 7 and damage will again occur. In both these cases in which cam 14 causes interference, as there are more than the 5 or 6 30 short butt needles at each end out of action, it will be understood that interference with the yarn carriers also occurs.

The positions of the long and short butt 35 needles at the two extremes of oscillation of the cylinder are shown diagrammatically in Figs. 8 and 9, z and z' being the dividing points between the long and short butt needles. Stop piece w is here shown out of action, as it will be in every case except at just 40 the danger time described. At that time stop piece w is caused to move inwardly toward the needle cylinder. More definitely, this movement is caused to take place just 45 prior to the end of throw of the last oscillation when the needles stand about as shown in Fig. 10, which shows some 5 or 6 of the short butt needles still out of action. Comparing this with Fig. 8 will show that there 50 is just about room enough between the extreme position line and stop piece w for this many butts without acting upon the stop piece. If, however, more of the short butt needles are still up out of action at this 55 time, which as we have seen would cause interference and damage, in the completion of its movement to extreme position, the cylinder will carry the butts up to and beyond stop piece w and the latter will be forced 60 out as shown in Fig. 11. This movement of the stop piece will stop the machine, through the described mechanism, as follows: As stop piece w is carried by bell crank v , its movement will turn the bell crank and cam u . 65 will press pin t to the left, Fig. 5. This

movement of the pin t turns rod r so that arm x thereon acts upon pin 7 to trip off the stop mechanism.

If it occurs that the change takes place so soon after the down pickers have been 70 made operative that there are only a few of the needles remaining knitting at the time, then, when the stop piece is pressed in toward the cylinder, it will strike some of the butts and be prevented from completing its movement. In this case, in the raising of rod r pin t will slide upon cam u , and will be forced to turn, pressing arm x below against catch pin 7 and tripping 75 off the stop mechanism. Thus at every 80 change from oscillation to rotation, when a cam o is brought into action, the first movement will be to turn bell crank v . Unless there is some error in the timing, this bell crank can turn freely, but if all of the needles or too many of them are out of action, the stop piece w will either be prevented from approaching the cylinder in its full movement, or having approached will be forced out again by the extra needle butts, 85 in both cases turning rod r , and actuating the stop mechanism as described.

It will be understood that the special embodiment of the invention hereinbefore described, acts upon the upper row of needle butts, *i. e.*, those which are out of action. At the time of danger, a stop piece is brought 95 against the needle cylinder in line with the upper line of butts, normally with an idle movement, but if there are too many of these butts the movement of the stop piece is effective to cause the machine to stop and prevent injury. Such a result may also be brought about by mechanism co-acting with the lower line of butts. A stop piece may be pressed toward the needle cylinder in line with the active butts and normally strike them and not be allowed to complete the movement. If, however, there are not as 100 many active butts as there should be, the stop piece will be pressed in against the cylinder and this movement caused to stop the machine.

I do not wish, therefore, to limit the scope 115 of my invention merely to stop mechanism acted upon by the upper line of butts, but intend to include stop mechanism controlled by the butts of needle, whether active or inactive, as one or the other may be found more convenient to use in a given machine.

A form of mechanism for acting on the 120 lower line of butts is shown in Figs. 13, 14, 15 and 16. As in the first described form of my invention, a vertical rod r' is mounted in brackets on the machine, and carries at its lower end an arm x' for acting upon latch pin 7 for tripping off the stop mechanism. Mounted on the upper end of rod r' is an arm carrying a stop piece w' in line with the butts of the active needles, l . Rod r' 125

also carries a finger p' in line of travel of an annular cam o' mounted to rotate with cam disk g . A spring 5 holds finger p' against cam o' and arm x' in position to act upon latch pin 7. However, cam o' , being circular, prevents arm x' from acting during the movement of the cam disk, except at the danger point. At these points cam o' is furnished with a depression 4 for finger p' which would allow arm x' to trip the stop mechanism. However, at these points, stop piece w' should strike the butts of active needles and prevent the turning of rod r' and the tripping of the stop mechanism. Therefore if the finger does move in against the cylinder at this time, and the arm x' trips pin 7 to stop the machine, it is because not enough needles had been brought back into action; in other words, because the change to rotation had been brought about prematurely, which would occasion the threatened damage to the machine, already described, if it were not prevented from having that effect by the actuation of the stop mechanism.

Having now fully described my invention, what I claim and desire to protect by Letters Patent is:

1. In automatic stops for circular knitting machines, in combination, a needle cylinder, vertically movable needles therein provided with butts, mechanism to stop the machine and a contrivance adapted to actuate the stop mechanism and controlled in its operation by the butts of needles.

2. In automatic stops for circular knitting machines, in combination, a needle cylinder, vertically movable needles therein provided with butts, mechanism to stop the machine, and a contrivance connected with the stop mechanism and movable toward and from the needle cylinder and located in operative relation to the butts of certain needles when the same are in one of their vertical positions and adapted to be controlled in its operation by said butts.

3. In automatic stops for circular knitting machines, in combination, a needle cylinder, vertically movable needles therein, mechanism for stopping the machine, and a contrivance adapted to control the operation of the stop mechanism and a part whereof is adapted to move into the space occupied by the butts of certain needles when the same are in one of their vertical positions and controlled in its operation by the position of said butts.

4. In automatic stops for circular knitting machines, in combination, a needle cylinder, vertically movable needles therein, mechanism for stopping the machine, and a contrivance adapted to control the operation of the stop mechanism and a part whereof is adapted to move into the space occupied by the butts of certain needles when the same

are in one of their vertical positions and controlled in its operation by the position of said butts, and pattern mechanism independently controlling the positioning of the needle and the movement into operative position of said contrivance.

5. In automatic stops for circular knitting machines, in combination, a needle cylinder, vertically movable needles therein provided with butts, mechanism to stop the machine, and a contrivance operable by the butts of needles to actuate the stop mechanism.

6. In automatic stops for circular knitting machines, in combination, a needle cylinder, vertically movable needles therein, mechanism for stopping the machine, and a contrivance a part whereof is adapted to move into the space which is occupied by the butts of certain needles when the same are in one of their vertical positions and adapted to be engaged by the butts of the needles when the same are in such position and to be thereby operated to actuate the stop mechanism.

7. In automatic stops for circular knitting machines, in combination, a needle cylinder, vertically movable needles therein, mechanism for stopping the machine, and a contrivance a part whereof is adapted to move into the space which is occupied by the butts of certain needles when the same are in one of their vertical positions and adapted to be engaged by the butts of the needles when the same are in such position and to be thereby operated to actuate the stop mechanism, and pattern mechanism independently controlling the positioning of the needles and the movement into operative position of said contrivance.

8. In automatic stops for circular knitting machines, in combination, a needle cylinder, vertically movable needles therein provided with butts, mechanism to stop the machine, a lever movable into the space occupied by the butts of certain needles when the same are in one of their vertical positions, and connections between said lever and the stop mechanism adapted to be rendered operative to operate the stop mechanism dependent upon whether or not the butts of said needles obstruct said movement of the lever.

9. In automatic stops for circular knitting machines, in combination, a needle cylinder, vertically movable needles therein provided with butts, mechanism to stop the machine, a lever adapted to be moved into the space occupied by the butts of certain needles when the same are in one of their vertical positions, and a device between said lever and said stop mechanism adapted to be actuated to so move said lever and to be itself actuated by said lever, upon engagement of the latter with the butts of said needles, to operate the stop mechanism.

10. In automatic stops for circular knitting machines, the combination with the needle cylinder and the needles therein, said needles provided with butts and slidable vertically into and out of action, of pattern mechanism adapted to control the movement of said needles into and out of action, a contrivance a part whereof is adapted to be moved by the pattern mechanism into a space occupied by butts of certain needles when the same are in one of their vertical positions, and mechanism for stopping the machine connected with and adapted to be actuated by said contrivance when the same 10 engages the butts of the needles.
11. In automatic stops for circular knitting machines, the combination with the needle cylinder and the needles vertically slidable therein into and out of action, said needles provided with butts, of a contrivance a part whereof is normally out of the path of the butts of both active and inactive needles but which is adapted to be moved into a space occupied by butts of certain needles when the same are raised to an inactive position and timed normally to be moved into such space when such needles are lowered to an active position, pattern mechanism adapted to control the movement of 20 said needles into and out of action and adapted also to actuate said contrivance, and mechanism for stopping the machine connected with and adapted to be actuated by said contrivance when the butts of improperly raised needles engage the same.
12. In automatic stops for circular knitting machines, the combination with the needle cylinder and the needles, provided with butts, vertically slidable therein into 20 and out of action, of pattern mechanism adapted to control the movement of said needles into and out of action, a lever adapted to be moved into a space occupied by butts of certain needles when the same are 40 in one of their vertical positions, a device having two movements and adapted to be given one of said movements by the pattern mechanism, a cam engagement between said device and lever adapted to transmit the last-named movement of the device to the lever and adapted also to give to said device its second movement upon engagement between the butts of misplaced needles and 50 said lever, and stop mechanism actuatable by said device in the second of its differential movements.
13. In automatic stops for circular knitting machines, the combination with the needle cylinder and needles vertically slidable therein into and out of action, said needles provided with butts, of a step-by-step actuated pattern disk adapted in certain of its movements to control the movement of said needles into and out of action, a regularly operated pattern chain having lugs irregularly spaced apart adapted to control the actuation of said disk, a contrivance a part whereof is normally out of the paths of the butts of active and inactive needles but which is adapted to be moved into a space which is occupied by butts of certain needles when the same are raised to an inactive position and timed normally to be moved into such space when such needles are lowered to an active position, connections from the pattern disk adapted to so actuate said contrivance, and mechanism for stopping the machine connected with and adapted to be actuated by said contrivance when, due to misplacement of the pattern chain relative to the pattern disk, the butts of improperly raised needles operate to obstruct or displace said contrivance.
14. In automatic stops for circular knitting machines, the combination with the needle cylinder and the needles therein, said needles provided with butts and slidable vertically into and out of action, of pattern mechanism adapted to control the movement of said needles into and out of action, a lever adapted to be moved into a space occupied by butts of certain needles when the same are in one of their vertical positions, a vertically movable and turnable rod, pattern mechanism adapted to vertically move the rod, a cam connection between the rod and lever whereby the lifting of the rod operates the lever and the lever, if obstructed or displaced by engagement with the butts of improperly positioned needles, turns the rod, and mechanism to stop the machine adapted to be actuated by the turning of the rod.

In testimony of which invention, I have hereunto set my hand, at Philadelphia, on this 15th day of January, 1916.

HAROLD E. HOUSEMAN.
